Henry M. Herbener,

By Attorney

UNITED STATES PATENT OFFICE.

HENRY M. HERBENER, OF MEMPHIS, TENNESSEE, ASSIGNOR, BY MESNE ASSIGNMENTS, TO CONSOLIDATED MATTRESS CO., OF BOSTON, MASSACHUSETTS, A CORPORATION OF MASSACHUSETTS.

METHOD OF AND APPARATUS FOR PRODUCING MATTRESSES.

Application filed May 22, 1924. Serial No. 715,227.

My invention relates to a method of and apparatus for producing mattresses.

In accordance with my method, I contemplate taking the linters from a linter gin 5 and introducing the same to the screen drum of a condenser. Instead of obtaining the linters from a linter gin that is ginning the cotton seed, I may introduce into this gin previously baled linters, and regin the same 10 to aerate it, or may pass the baled linters through a willow or opener and pass this reginned or aerated linters to the condenser. I also contemplate reginning or aerating cotton and cotton waste, thereby using cotton 15 fibre which has been reginned or aerated. The layer of cotton fibre or linters, thus ginned or reginned, or aerated, is removed from the condenser drum or screen and passed over a lapper which arranges the 20 same in layers, in a stepped manner, upon a continuously traveling endless belt, producing a felt. The felt thus produced is built up to the proper thickness for a mattress and may be torn or cut at suitable 25 points, producing a section of felt of the desired length for the mattress. This cut section of felt may now be suitably compressed and fed into the tick or casing of a mattress, which is removed from the stuffing 30 machine and transferred to the sewing machine. A new tick is at once placed upon the stuffing machine. I also contemplate a somewhat simplified method, in which the felt is first compressed and fed into the tick, 35 and then torn, or cut when the tick is filled.

By virtue of this method, I am enabled to handle the linters or cotton fibre, directly from the condenser, and supply the same into the tick, in a continuous and expeditious 40 manner.

In the accompanying drawings forming a part of this specification, and in which like numerals are employed to designate like parts throughout the same,

Figure 1 is a plan view, partly diagrammatic, of apparatus embodying my invention, parts broken away,

Figure 2 is a side elevation of the same,

Figure 3 is a side elevation of the mattress 50 stuffing machine, and associated elements,

Figure 3^a is a central longitudinal section through a stationary chute or slide,

Figure 4 is a side elevation of a modified form of mattress stuffing machine,

Figure 5 is a similar view of a further modified form of mattress making machine,

Figure 6 is a side elevation of a further modified form of the invention, and,

Figure 7 is a side elevation of the combs.

In the drawings, wherein for the purpose of illustration is shown a preferred embodiment of my invention, the numeral 10 designates a cotton or linter gin or regin, preferably of the construction shown in my copending application for method of producing felt from cotton and linter fibre, filed February 15th, 1924, Serial No. 693,136. This gin is adapted to remove the linters from the cotton seed, and to aerate the same. Leading into the top of the linter gin casing 70 10 is a suction pipe 11, leading to the casing of a condenser 12, within which is rotated the usual screen drum 13. The casing has communication with a suction fan or blower 14. The linters or cotton fibre accumulates upon the upper surface of the screen drum 13, and is removed therefrom by rollers 15, and the layer of linters or cotton fibre is then passed upon a lapping machine 16. This lapping machine embodies an 75 endless conveyor passed over a frame 17, pivotally supported at 18, to swing in a vertical plane. The movable end of the frame is pivoted to the companion frame 19, and this companion frame has its opposite end supported by wheels 20, which travel upon a track 21. The usual means is employed to cause the lower end of the frame 19 to travel back and forth upon the horizontal track 21, whereby the frame sections 19, at their upper ends, reciprocate vertically. By this means, the layer of linters or cotton fibre is distributed in layers, in stepped relation, upon a continuously traveling endless belt 22. The construction of the lapper is generally that shown in the ordinary camel-back lapper, although other forms of lappers can be used.

The endless belt 22 is preferably slightly inclined, and is adapted to discharge the felt produced thereon by the lapping operation, upon a gravity operated conveyor, which is inclined and embodies a plurality of idler rollers 23. The gravity operated conveyor, Figure 3^a, may also be in the form of an inclined stationary chute, embodying an inclined bottom 23^a and sides 23^b. The felt slides down this inclined chute. Prior to

the passage of the felt upon this gravity conveyor, the felt is preferably torn or cut into a desired length. This is accomplished by passing the felt between upper and lower rollers 24 and 24' and 25 and 25'. The rollers 24 and 24' are not vertically movable and are driven at the same speed. The rollers 25 and 25' are vertically movable, and rotate in the same direction as the rollers 24 and 24', but at a higher rate of speed. When the rollers 25 and 25' are moved inwardly so that they engage with the cotton felt, they pull, tear or break the same at this point, producing the section 26, of the desired length to pass into the mattress casing. The gravity conveyor is convenient, inasmuch as it produces a slight intermittent feed of the felt section and the mattress stuffing machine, thus giving sufficient time to remove the previously stuffed casing or tick and to place another casing or tick thereon.

The gravity conveyor discharges upon an endless conveyor 27, included in a mattress stuffing machine. The endless conveyor 27 is preferably horizontally arranged, and above it is an inclined endless conveyor 28, the conveyors traveling in the direction of the arrows. The conveyors 27 and 28 are therefore arranged in a wedging relation, tapering forwardly, toward the nozzle 29. This nozzle is preferably slightly transversely tapered, increasing in width forwardly. The nozzle receives thereon the open end or side of the tick or casing, which is supported upon the rolling table 30 when filled. The section of felt thus passed between the endless belts 27 and 28, is compressed, and fed through the nozzle 29 into the tick, and supported upon the table 30. The table is then rolled to the sewing machine, and the open end of the stuffed tick is sewed as it passes under the sewing machine, after which the table 30 is returned to the stuffing machine, to receive another tick filled with felt from the nozzle 29. The next cut section of felt will then be fed to the stuffing machine and into the mattress ticking.

In Figure 4 I have shown a slight modification of the mattress stuffing machine. In this modification, the upper inclined endless belt 28 is dispensed with, and a coacting cylinder 28' substituted therefor. The felt is pressed between the cylinder 28' and the endless belt 27 and is fed through the nozzle 29.

In Figure 5 I have shown a further modification of the stuffing machine. The endless belts 27 and 28 are dispensed with, and the rollers 23 of the gravity conveyor passed directly to cylinders 31, which serve to compress the felt and force it through the nozzle 29. All other parts of the apparatus remain the same.

In Figure 6 I have shown a further modi-

fication of the invention. The gravity conveyor, and the cutting of the felt before it passes thereon, is dispensed with. The endless belt 22, upon which the layers of linters or cotton is lapped, discharges through a passage between the belt 22 and a compression roller 31, which serves to compress the felt and force it through a nozzle 32, having the mattress casing thereon, which is later supported by the table 30, as it becomes filled with felt. Arranged near the discharge end of the nozzle 32 are upper and lower vertically movable combs 33 and 34. These combs are normally arranged out of engagement with the mattress casing and above and below the discharge end of the nozzle. After a suitable amount of felt is thus fed into the casing, the casing is removed from the nozzle, and the combs 33 and 34 moved inwardly and penetrate the felt. The upper comb may be employed to hold the felt against movement while the lower comb may be moved toward the table 30, thus tearing or breaking the felt. The invention is in no sense restricted to this particular means of cutting, tearing or breaking of the felt, as other means may be employed, such as rollers, blades or the like.

It is to be understood that the forms of my invention herewith shown and described, are to be taken as preferred embodiments of the same, and that various changes in the shape, size, and arrangement of parts may be resorted to, without departing from the spirit of my invention, or the scope of the subjoined claims.

Having thus described my invention, I claim:

1. The herein-described method of producing a mattress, which comprises depositing fibre upon a revolving screen in the presence of an air current, removing the layer of fibre thus deposited and continuously lapping the same for producing a felt of the proper thickness for a mattress while effecting the longitudinal travel of the felt, immediately compressing the felt thus produced and passing a suitable length of the same into a mattress casing, and removing the mattress casing and sewing up the same.

2. The herein-described method of producing a mattress, which comprises lapping a layer of linters, cotton or fibre upon a traveling support, for producing felt the correct thickness for a mattress, receiving the felt from the discharge end of the support and immediately compressing the same and passing the same through a nozzle holding thereon a mattress casing, and removing the mattress casing and sewing the same.

3. The herein-described method of producing a mattress, which comprises lapping a layer of linters, cotton, or fibres upon a traveling support for producing felt of a suitable thickness to properly fill a mattress,

dividing the felt thus produced into sections of suitable length, independently effecting the longitudinal travel of each section and immediately compressing the same, 5 and passing the compressed section through a nozzle receiving thereon a mattress casing, and removing the casing and sewing the same.

4. The herein-described method of producing a mattress, which comprises lapping a layer of linters or cotton fibre upon a traveling support for producing felt the proper thickness for a mattress, while effecting the continuous movement of the felt, dividing 10 the traveling felt into sections of suitable length for filling a mattress casing, effecting an intermittent longitudinal travel of each section, immediately suitably compressing each section after the intermediate travel, 15 passing the compressed section through a nozzle having a mattress casing thereon, and removing the mattress casing after being filled and sewing the same.

5. In apparatus of the character described, a traveling support, means for lapping fibrous material upon the support for producing a felt, an idle conveyor, and a felt compressing apparatus, all of said devices being arranged to receive the material one 20 from the other, means to cut the felt into suitable lengths as it discharges from the traveling support, and a nozzle for the reception of a mattress ticking arranged at the discharge end of the compressing 25 means.

6. In apparatus of the character described, a conveyor, means for lapping fibrous material upon the conveyor for producing a felt, a felt compressing apparatus 30 arranged at an elevation beneath the conveyor, a nozzle to receive the felt from such apparatus, an inclined gravity operated roller conveyor connecting the conveyor belt and the compressing apparatus, and apparatus to cut the felt in suitable lengths as it 35 discharges from the conveyor belt.

7. The method of producing mattresses, comprising the steps of lapping a selected 40 number of layers of condensed aerated fibrous material into a felt, thereby producing such felt in the proper thickness to fill the mattress casing, compressing the original 45 felt thus produced, and then passing the

same into the mattress casing, all of such steps being carried out in a substantially 55 continuous corelated manner.

8. The method of producing mattresses, comprising the steps of lapping a selected 60 number of layers of condensed aerated fibrous material into a felt, thereby producing such felt in the proper thickness to fill the mattress casing, and also forming the felt in a proper width and length to fill the mattress casing, then compressing the 65 felt thus produced, and passing the same into the mattress casing, all of said steps being carried out in a substantially continuous corelated manner.

9. The method of producing mattresses, comprising the steps of lapping a selected 70 number of layers of condensed aerated fibrous material into a felt, thereby producing such felt in the proper thickness to fill the mattress casing, and also forming the felt in a proper width and length to fill 75 the mattress casing, effecting the travel of the felt from the lapping position and immediately compressing the same, and then feeding the same in the mattress casing, all of such steps being carried out in a sub- 80 stantially continuous corelated manner.

10. The method of producing mattresses, comprising the steps of condensing aerated fibrous material upon a revolving screen, removing the condensed fibrous material and 85 lapping a selected number of layers of the same into a felt having the proper thickness to fill the mattress casing and also forming the felt in a width and length to fill the mattress casing, effecting the travel of the 90 felt from the lapping position and compressing the same, and passing the felt into the mattress casing.

11. The method of producing mattresses, comprising the steps of lapping a continuous 95 layer of condensed aerated fibrous material into a selected number of layers to produce a felt in the proper thickness to fill the mattress casing, compressing the original felt thus produced and then passing the same into the mattress casing, all of said steps being carried out in a substantially continuous co-related manner.

In testimony whereof I affix my signature.

HENRY M. HERBENER.
